(57) **CLAIM**

The ornamental design for a vent with rectangular box and peripheral flange, as shown and described.

DESCRIPTION

FIG. 1 is an isometric view of a vent with rectangular box and peripheral flange showing my design;
FIG. 2 is a top view thereof;
FIG. 3 is a front elevational view thereof;
FIG. 4 is a rear elevational view thereof;
FIG. 5 is a bottom view thereof;
FIG. 6 is a left side elevational view thereof, the right side elevational view being a mirror image; and,
FIG. 7 is a cross sectional view taken along lines 7—7, as shown in FIG. 4 to illustrate an interior screen holding flange.
